UNITED STATES PATENT OFFICE

PERCY E. HUNTER, OF PITTSBURGH, PENNSYLVANIA

ANNEALING APPARATUS

Application filed May 11, 1931. Serial No. 536,476.

My invention relates to annealing apparatus, and more particularly to a base and its framework, for supporting annealing boxes.

One object of my invention is to provide an annealing base structure of such form that it is of light weight compared to cast steel structures and which nevertheless is possessed of great strength.

Another object of my invention is to provide a structure of the character referred to of such form that the tendency toward distortion through differences in temperature is minimized.

A further object of my invention is to provide a tray or similar support for annealing boxes that is of thinner wall thickness than various types heretofore employed, whereby there is more effective and uniform heating of the interior of an annealing box placed on said tray.

Still another object of my invention is to provide an annealing base structure of generally simplified and improved form.

Some of the forms which my invention may take are shown in the accompanying drawings wherein Figure 1 is a plan view of one structure; Fig. 2 is a fragmentary side elevational view thereof, on an enlarged scale; Fig. 3 is a view taken on the line III—III of Fig. 1; Fig. 4 is a view taken on the line IV—IV of Fig. 2; Figs. 5 and 6 are views taken on the lines V—V and VI—VI, respectively, of Fig. 1, and Fig. 7 is a view similar to Fig. 4, but showing a modification.

The base structure is intended to be employed with an annealing box 10 that is of course used in an inverted position to enclose a pack of sheets or other articles carried by the base during the heat-treatment thereof. The edge of the box 10 is provided with a channel-like rim portion 11 that extends into a sand-containing trough 12, the sand being employed to effect a seal between the interior of the box and the heated gases surrounding the same. The annealing box may, of course, be of any well-known form.

The base structure is preferably formed of sheet metal, various portions whereof are held in unitary relation by welding them together or in any other suitable manner. The sheet

metal is preferably of an alloy material that is capable of withstanding high temperatures and has a greater coefficient of expansion than ordinary sheet steel.

The under-frame of the base is provided with longitudinally-extending members 14 of I-beam form in cross section, but which may be suitably formed by welding two channel members back to back, as shown more clearly in Fig. 3. Cross beams 15 of channel form are welded to the longitudinal beams 14 at their points of juncture therewith. Thus, as shown more clearly in Figs. 2 and 3, the longitudinally-extending beams 14 have their webs punched out as indicated at 16 and the cross beams 15 are slid into place transversely of the base by inserting them through these openings 16. The cross beams are then raised to bring their upper sides flush with the upper sides of the longitudinal beams, the cross beams 15 having cut-out portions 17, as shown in Fig. 5, for receiving the flanges of the beams 14.

The beams 15 are welded or otherwise connected to the beams 14 along their lines of contact where the beams cross one another. The beams 15 could be made in short sections with their ends fastened to the sides of the beams 14. In order to stiffen the assembled cross beams and longitudinal beams, gusset plates 18 (Figs. 3 and 4) are welded at their bottom and vertical edges to the lower flange and the web of the longitudinal beam 14, and the sides of these plates 18 are welded to the backs of the cross beams or channels 15.

Channel-like or inverted U-shaped plates 19 have flange portions welded to the undersides of the longitudinal beams and extend approximately the full length of the structure. These channel plates may serve as runways for balls 20 upon which the table or base may be rolled into and out of a furnace, the balls 20 being employed instead of wheels. A drag bar 22 is of loop form at its outer end and has its inner ends 23 welded to the two intermediate longitudinal beams. A strut bar 24 is secured to these beams at a point adjacent to the ends 23. The drag bar

is, of course, utilized to pull and push the base from place to place.

In order to permit of convenient lifting and transporting of the base by crane hooks or the like, pairs of channels 26 (Figs. 1 and 4), are welded at their ends to adjacent sides of two cross beams 15, a plate 27 being welded to the bottoms of the channels 26. Bars or plates 28 are welded within each of the channel members 26 to stiffen the same and prevent bending or buckling of the channels when lifting force is imposed against the underside of the plate 27. Filler plates 29 are interposed between the upper sides of the channels 26 and the sand trough 12.

Gusset plates 18a are welded at their outer edges to the adjacent channel 26 and at their inner and lower edges to the longitudinal beams, as shown more clearly in Figs. 2 and 4.

A pan or load-supporting tray 30 is provided with a series of lugs 31 whose free ends are bent or offset downwardly to form grooves for the reception of flanges of I-beams 14, as shown more clearly in Figs. 1 and 3, these lugs being welded to the tray and serving to hold it down and against shifting transversely of the under-frame, but nevertheless permitting expansive and contractive movements of the tray with respect to the under-frame. Stop lugs 32 are welded to the underside of the tray as shown more clearly in Figs. 1 and 6 to prevent shifting of the tray longitudinally of the under-frame.

The edges of the tray are bent over to form grooves or channels for the reception of the upturned inner edges 34 of the sand trough 12, clearance being provided between the edges 34 and the tray 30, so that the tray and the sand trough may expand and contract independently of one another. A series of plates 35 are welded edgewise to the bottom of the sand tray, so that they will support the cover 10 in spaced relation to said bottom and permit sand to be pushed to the inner side of the box wall in order that the lower edge of the box will be completely buried in sand to provide the necessary air seal. Webs or gussets 37 are welded to the bottom and the outer wall of the sand trough to stiffen the same.

The sand trough is made in vertically-divided sections, each of which may expand and contract relative to one another, the sections being bridged by plates 38, as shown more clearly in Figs. 3 and 5. These plates are of hook form at their outer end to maintain the adjacent ends of two trough sections in alinement, and their inner ends are turned upwardly against the inner side of the trough sections, in order to bridge the spaces between the end sections throughout their entire width. Each of the plates 38 may be welded or otherwise secured to one of the trough sections with which it is associated.

Referring now to Fig. 7, I show a structure somewhat similar to that of the other figures, the principal difference being in the substitution of a wheel 40 for the balls 20. The wheels 40 are journaled in suitable bearings 70 formed in the lower edges of two of longitudinal beams 41, whose ends are welded to two cross beams 15a. Since the beams 15a do not extend through the beams 14a and 41, and therefore are of short length relative to the beams 14, I provide tie rods or bars 42 which are welded at their ends to the extremity of the beams 15a.

It will be seen that throughout the major portion of the bottom of the tray, namely at 80 the points between the beams, there is only a single thickness of sheet metal through which the heat has to be transmitted to the interior of the annealing box. Therefore, there are better and more uniform heating conditions 85 within the box than would be the case if the table or tray were of considerably greater thickness.

It will therefore be seen that I provide annealing apparatus wherein the tray and the 90 supporting runways for the rollers are formed as a unitary part of the tray structure, including the provision of a sand seal for the edges of the box, without the necessity of providing a separate bottom member. 95

I claim as my invention:—

1. Annealing apparatus comprising a tray portion for supporting articles to be annealed, and a trough portion for supporting an annealing box, one of said portions having its edges bent in vertical directions to form a groove, and the other portion having its edge bent to form a flange fitting within said groove. 100

2. Annealing apparatus comprising a tray portion for supporting articles to be annealed, and a trough portion for supporting an annealing box, one of said portions having its edges bent in vertical directions to form a groove, and the other portion having 110 its edge bent to form a flange fitting within said groove, clearance being provided between said edges to permit relative expansive and contractive movements of said members.

3. Annealing apparatus comprising a tray portion for supporting articles to be annealed, and a trough portion for supporting an annealing box, one of said portions having its edges bent in vertical directions to form a groove, and the other portion having its edge bent to form flanges fitting within said groove, the trough portion being divided into sections along transverse lines to permit expansion and contraction of the sections independently of one another. 115

4. Annealing apparatus comprising a tray portion for supporting articles to be annealed, a trough portion for supporting an annealing box, one of said portions having its edges bent in vertical directions to form a 120

- groove, and the other portion having its edge bent to form flanges fitting within said groove, the trough portion being divided into sections along transverse lines to permit to sections along transverse lines to permit 5 expansion and contraction of the sections independently of one another, and bridging plates overlying the lines of division between the trough sections.
5. Annealing apparatus comprising a tray 10 portion for supporting articles to be annealed, a trough portion for supporting an annealing box, one of said portions having its edges bent in vertical directions to form a groove, and the other portion having its edges bent to form flanges fitting within said groove, the trough portion being divided into sections along transverse lines to permit expansion and contraction of the sections independently of one another, and bridging plates 15 overlying the lines of division between said trough sections, the outer edges of the plates being bent to partially embrace the outer edges of two adjacent trough sections.
6. Annealing apparatus comprising a tray 20 portion for supporting articles to be annealed, a trough portion for supporting an annealing box, one of said portions having its edges bent in vertical directions to form a groove, and the other portion having its edge bent to form flanges fitting within said groove, the trough portion being divided into sections along transverse lines to permit expansion and contraction of the sections independently of one another, and bridging plates 25 overlying the lines of division between said cross sections, the outer edges of the plates being bent to partially embrace the outer edges of two adjacent trough sections, and the inner edges of said plates extending 30 into the said groove.
7. Annealing apparatus comprising a tray 40 for supporting articles to be annealed, a trough disposed in proximity to the said tray and adapted to receive the lower edge of an annealing box, and spacer strips in said trough for supporting the edge of the annealing box in spaced relation to the bottom of the trough.
8. Annealing apparatus comprising a tray 45 for supporting articles to be annealed, a trough disposed in proximity to the said tray and adapted to receive the lower edge of an annealing box, and spacer strips in said trough for supporting the edge of the annealing box in spaced relation to the bottom of the trough, the said strips extending transversely of the trough and being secured to the bottom and one side thereof.
9. Annealing apparatus comprising a tray, 55 a sand trough, and means for maintaining the trough and the tray in assembled relation, but permitting relative expansive and contractive movements thereof.
10. Annealing apparatus comprising a tray, 60 a sand trough, and means for maintaining the trough and the tray in assembled relation, but permitting relative expansive and contractive movements thereof.

space between adjacent edges of the tray and the trough for holding them in unitary relation, but permitting relative expansive and contractive movements thereof.

11. Annealing apparatus comprising a tray 70 having its edges bent to inverted channel form and a sand trough having its inner edges extending into the said channel.

12. Annealing apparatus comprising a frame, 75 a tray mounted on said frame and having downwardly-extending lugs interengaging with the frame, clearance being provided between the said lugs and the frame, to permit expansive movements of the tray in certain directions independently of the frame.

13. Annealing apparatus comprising a frame, 80 a tray, means for maintaining the tray in assembled relation on said frame, a trough supported by said frame, and inter-engaging means between the trough and the tray for maintaining the trough in position on the frame.

14. Annealing apparatus comprising a frame, 85 a tray, means for maintaining the tray in position on said frame, a trough supported by said frame, and inter-engaging means between the trough and the tray for maintaining the trough in position on the frame, the last-named means permitting relative expansive and contractive movements of 90 the trough and the tray.

15. Annealing apparatus comprising a frame, 95 a tray, means for maintaining the tray in position on said frame, a trough supported by said frame, and inter-engaging means between the trough and the tray for maintaining the trough in position on the frame, the trough being divided into sections along 100 transverse lines.

16. Annealing apparatus comprising a frame, 105 a tray member, a trough member, means for maintaining one of said members in position upon the frame, and inter-engaging means between the said members for maintaining the other member in position 110 upon the frame.

17. Annealing apparatus comprising a frame, 115 a tray member, a trough member, means for maintaining one of said members in position upon the frame, and inter-engaging means between the said members for maintaining the other member in position upon the frame, and arranged to permit relative expansive and contractive movements of 120 said members.

18. A framework for supporting annealing boxes and the like, comprising a set of longitudinally-extending beams, and a set of transversely-extending beams, each set of beams being substantially continuous, and the respective beams of the two sets being cut away at their points of intersection to permit them to lie in a common plane.

19. A framework for supporting annealing boxes and the like, comprising a set of 130

longitudinally-extending beams, and a set of transversely-extending beams, each set of beams being substantially continuous, and the respective beams of the two sets being cut 5 away at their points of intersection to permit them to lie in a common plane, the beams being of sheet metal and connected together at their points of contact.

20. Tray structure for annealing boxes, 10 comprising a tray member, an under-frame therefor composed of longitudinally-extending beams, and channel members extending parallel to the beams and secured at their edges thereto, the channel members being 15 mounted in inverted position to serve as runways for anti-friction rollers.

21. Tray structure for annealing boxes, comprising a tray member, an underframe for the tray having beams extending longitudinally thereof, and channel members secured at their edges to the undersides of the beams, the channels being in inverted position and serving as runways for anti-friction rollers.

25. 22. Tray structure for annealing boxes and the like, comprising a tray, an underframe therefor, the said underframe being provided with beams extending longitudinally thereof, and means on said beams for engaging 30 with anti-friction members.

23. Annealing apparatus comprising a tray, a sand trough, and means for maintaining the trough and the tray in assembled relation, but permitting relative expansive and 35 contractive movements thereof, and means connected with the tray for maintaining anti-friction supporting members in operative relation thereto.

In testimony whereof I, the said PERCY E. 40 HUNTER, have hereunto set my hand.
PERCY E. HUNTER.
